UNITED STATES PATENT OFFICE

WILLIAM J. DAVID, OF BURBANK, CALIFORNIA

ADJUSTABLE NECKBAND FOR BARBERS' HAIR CUTTING CLOTH

Application filed October 15, 1928. Serial No. 312,537.

My invention is an adjustable neck band for barbers' haircutting cloth.

An object of my invention is the construction of an adjustable neck band which may be attached to hair cutting cloths or the like so that a barber may readily attach the cloth around a person's neck. In this connection a further object of my invention is constructing the neck band so that there are no metallic parts and so that there are no elements of construction such as hooks or eyes which require to be removed before sending the cloth to the laundry.

A further detail object of my invention is therefore the construction of a neck band for haircutting cloths of such character that the barber may utilize the cloth directly as it comes from the laundry without needing to apply attachments thereto and that when sending the soiled cloths to the laundry it is unnecessary to disconnect any of the fastening devices.

A more specific object of my invention is the construction of a neck band for the purpose above mentioned having a series of loops formed of tape or the like through any of the loops of which a fastening tape or string may be passed and thereby the neck band and cloth may be quickly adjusted to a person's neck.

In constructing my invention I utilize a fabric tape of sufficient length to pass around a very large neck and to overlap. The tape has a series of fabric loops preferably formed of a smaller tape extending from one end part way along the main tape and at the other end of the main tape there are strings or other fastening tapes which are adapted to pass through the loops and be tied in a knot. By having a series of loops the neck band may be readily adjusted to necks of various sizes. The main tape may be stitched directly to the haircutting cloth or may have a secondary tape attached thereto and this tape may be secured to the cloth.

My invention is illustrated in the accompanying drawings in which:

Figure 1 is a view showing the neck band stretched around a person's neck before securing such band in position;

Fig. 2 is a view similar to Fig. 1 showing the neck band in the fastened position;

Fig. 3 is a side view of the neck band illustrating my invention as attached to a haircutting cloth;

Fig. 4 is an elevation showing the manner of tying the neck band to the loops;

Fig. 5 is a perspective view of part of the neck band;

Fig. 6 is an enlarged vertical section through the neck band as if taken on the line 6-6 of Fig. 3.

Referring to the drawings, the numeral 11 designates the haircutting cloth having the neck band 12 thereon, the neck band being adapted to form a close fit around a person's neck. The neck band is preferably made of a main tape 13 which is folded at 14, the edges and the tape being brought close together as indicated at 15. Around this folded tape there is wound a secondary tape 16 having loops 17 in the front of the main tape and on the back of the main tape the secondary tape fits smoothly as indicated at 18. The winding of the secondary tape may be considered as made with the portions 17 of the loop and the portions 18 crossing the main tape 13 in a diagonal manner, this being caused by the progressive advancing of the secondary tape. The main and secondary tapes are then stitched together by an upper and lower closing stitching 19, thus securely holding the loops on the main tape.

If desired this main tape may be directly secured to the haircutting cloth, but I prefer to use a third wider tape 20 of the same length as the main tape 13 and this is secured to the main tape and to the secondary tape by the same stitching 19. In this manner all of this longitudinal stitching may be done at one time; this then gives a wider construction to attach to the haircutting cloth.

It will be noted that the loops commence adjacent one end of the tape as indicated at 21 but they do not continue entirely the full length of the tape. At the opposite end 22 there is a pair of strings 23 these being preferably formed of a tape secured by stitching 24. The ends of these strings may be folded and stitched as indicated at 25 to give a type of

tip end suitable for threading through the loop.

In using my invention on the hair cutting cloth the cloth is fitted around a person's neck as indicated in Fig. 1 with the end 21 of the tape at about the center of the back of the neck. The end 22 having the string 23 is pulled further around the neck and the strings are passed through a convenient loop and then tied in a knot as indicated at 26, this illustrating a bow knot. This construction allows the haircutting cloth to be adjusted to necks of various sizes and to have a snug fit on such neck. Hence it will be seen that there is nothing that the barber need attach to this neck band when the haircutting cloth is received from the laundry and there is nothing to be removed when the device is sent to the laundry and as there are no metal parts the laundering is a simple operation and there are only fabric materials subjected to the washing and laundering operation.

Various changes may be made in the principles of my invention without departing from the spirit thereof as set forth in the description, drawings and claims.

I claim:

- 30 1. A neck band having a flexible main strip adapted to encircle a person's neck and to overlap, a secondary tape wound around the strip, the windings being spaced apart and secured to the main strip forming loops on the outside, and a fastening means to engage anyone of the loops.
- 35 2. A neck band having a main flexible tape, a second tape wound thereon and stitched to the first tape forming a series of loops on the outside of the main tape, and a flexible securing device adapted to engage through any one of the loops.
- 40 3. A neck band having a first or main tape, a secondary tape wound thereon passing over the outside and inside of the first tape, the windings being spaced lengthwise, a third tape wider than the first tape and on the inside thereof, stitching to secure the three tapes together, forming loops in the second tape on the outside of the first tape, the loops extending diagonally across the first tape, and a fastening means to engage anyone of said loops.
- 45 5. A haircutting cloth having a neck band with a series of loops on the outside of the band and spaced apart, the loops being diagonal, and a flexible fastening securable in any one of the loops.

In testimony whereof I have signed my name to this specification.

60 WILLIAM J. DAVID.
